Inventor,

Charles Hofstetter Jr.

*by A. B. Upham,
His Attorney.*

UNITED STATES PATENT OFFICE.

CHARLES HOFSTETTER, JR., OF PEORIA, ILLINOIS, ASSIGNOR OF TWO-THIRDS
TO FRANK HALL AND ADOLPHUS E. HALL, BOTH OF SAME PLACE.

CAR-HEATER.

SPECIFICATION forming part of Letters Patent No. 368,211, dated August 16, 1887.

Application filed June 19, 1886. Serial No. 205,610. (No model.)

To all whom it may concern:

Be it known that I, CHARLES HOFSTETTER, Jr., of Peoria, in the county of Peoria, State of Illinois, have invented an Improved Car-Heater; and I do hereby declare that the following is a full, clear, and exact description 5 of the invention, and of the manner and process of making the same, in which—

My invention relates to improvements in car-heaters, and is fully described and explained 10 in this specification, and illustrated in the accompanying drawings, in which—
Figure 1 is a sectional elevation through *xx* in Fig. 2 of one end of a car provided with my heating apparatus. Fig. 2 is a sectional plan 15 view of the same at *yy* in Fig. 1.

P represents the car-floor; *P'*, the front end thereof; *N*, the car-platform; *M*, one of the supporting-wheels, and *L* the axle thereof.

The air-conduit *A* has a portion of its length 20 formed in the spiral coil *B*, which is located within the furnace-wall *E*, and said air-conduit terminates in the perforated pipe *C*, lying upon the floor of the car or laid in a suitable groove therein, and preferably extending along the 25 center of the car-floor *P*. Below the coil *B* is the furnace-grate *E'*, and about the furnace-wall *E* is the envelope *D*, forming an air-chamber between itself and said wall.

D' represents the door for the insertion of 30 the fuel.

F is a fan-blower secured to the under side 35 of the car-floor and driven by power communicated thereto by means of the pulley *J*, located on the shaft *L*, its own pulley *H* and a belt, *K*, passing about the same. From said fan-blower extends the air-conduit *A*, so that when the car is in motion there is forced 40 through said conduit into the car a steady and strong stream of air thoroughly warmed by its passage through the hot coil *B*.

To obviate the necessity of supplying the 45 conduit *A* with cold air, which, when the temperature is very low, would waste much heat, I secure the conical plate *G'* over the open side of the fan-blower *F* and have the pipe *G* communicate therefrom to the air-chamber between the furnace-wall and its envelope or jacket. In this way the air for supplying the 50 fan and conduit comes from said chamber and is partially warmed prior to its admission to said conduit.

The car to which I have especially adapted

my heater is the ordinary tram or horse car; but I do not restrict myself thereto, as it is equally applicable to other cars, or, with suitable changes, to buildings. 55

The spiral coil *B*, I usually make in a flattened or elliptical form, as indicated in Fig. 2, in order that there may be passage-room between the front of the furnace and the platform-shield or dash-board. 60

In the drawings, my furnace is shown as located upon the front platform, for the convenience and comfort of the driver; but it can be placed beneath the car or elsewhere. 65

From the pipe *A* extends the small pipe or tube *R* up to the top of the furnace, where it terminates just below the lower end of the smoke-flue *E'*. Said upper extremity of the tube *R* being upwardly curved, a portion of 70 the air stream from the pipe *A* furnishes draft to the fire. The valve *R'* controls the amount of air entering said tube, and hence the draft. The coil *B*, through which the air passes from the fan to the car, forms the fire-pot of the 75 heater, thus insuring rapid and complete heating of the air as it passes through the coil.

What I claim as my invention, and for which I desire Letters Patent, is as follows, to wit:

1. In a car-heater, the combination, with a 80 combustion-chamber and a shell surrounding it and separated from it by a suitable air-space, of an air-heating coil lying within the combustion-chamber and communicating with the body of the car, a fan-chamber communicating with said air-space and said air-heating coil, and a fan lying within said chamber and adapted by its rotation to draw air from said air-space and force it through said coil, substantially as and for the purpose set forth. 85

2. In a car-heater, the combination of the 90 furnace, the air-heating coil located therein, the fan communicating with said coil, the air-inlet pipe, the smoke-flue, and the supplemental pipe communicating with the air-inlet pipe and the smoke-flue, substantially as described.

In testimony that I claim the foregoing invention I have hereunto set my hand this 15th day of June, in the year 1886.

CHARLES HOFSTETTER, JR.
